UNITED STATES PATENT OFFICE.

ERWIN O. E. VOLKMAN, OF MILWAUKEE, WISCONSIN.

LINOTYPE ASSEMBLING DEVICE.

1,314,836.

Specification of Letters Patent. Patented Sept. 2, 1919.

Application filed April 30, 1918. Serial No. 231,662.

To all whom it may concern:

Be it known that I, ERWIN O. E. VOLKMAN, a citizen of the United States, and resident of Milwaukee, in the county of Milwaukee and State of Wisconsin, have invented new and useful Improvements in Linotype Assembling Devices, of which the following is a description, reference being had to the accompanying drawings, which are a part 10 of this specification.

This invention relates to linotype machines and more particularly to the assembler for the matrices.

In the edge of each matrix is either one or 15 two letters or characters intaglio. The two-letter matrix bears two characters, one above the other, one of which may be a Roman face and the other an italic, small capital, or black face. If a line is to be composed 20 partly of the Roman face, which is in the upper position on the matrix, and partly of the other face, which is in the lower position, this has been accomplished heretofore by means of a shelf or ledge placed on the 25 assembly elevator in such a manner that it can be projected into the assembler or withdrawn from it at the will of the operator but in practice only one adjustment of the matrices with respect to each other for different 30 face type can be accomplished with this ledge and thereafter the matrices have to be "fingered" by the operator so that they may be perfectly placed upon the assembly elevator. To obviate this disadvantage it is 35 the object of this invention to provide an assembling device in which the matrices are assembled individually in either raised or lowered position without "fingering".

A further object of the invention is to 40 control the assembling of the matrices in either raised or lowered position from the key board of the machine.

A further object of the invention is to provide a new and improved form of feed from 45 the assembling rails to assembly elevator.

The invention further consists in the several features hereinafter described:

In the drawings:

Figure 1 is an elevation new of the assembler of a linotype machine, parts being 50 broken away;

Fig. 2 is front view of the device embodying the invention;

Fig. 3 is a section taken on the line 3—3'

of Fig. 2 and also showing part of the assembly elevator;

Fig. 4 is a section taken on the line 4—4 of Fig. 3.

Fig. 5 is a view of the device, parts being broken away and parts being shown in section showing it in position for delivering the matrices to their upper position.

Fig. 6 is a section taken on the line 6—6 of Fig. 5.

In Fig. 1 the numeral 5 designates the chutes through which the matrices move from the magazines (not shown), 6 the matrix belt by which the matrices are carried to the rails 7, 8 the assembler chute spring, 9 the assembler slide, 10 the assembler slide 70 brake and 11 the elevator as a whole. The belt 6 is driven from the pulley 12 mounted on the shaft 13. The assembly elevator includes the usual back rail 14, the front rails 15 and 16 and the movable ledges 17 and 18 75 which are separately controlled by the levers 19 and 20. All of these parts are old and well-known as is also their operation, the matrices passing from the chutes 5 being delivered by the belt 6 to the rails 7 from whence they are moved by a star wheel (not used in the present construction) to the rails of the assembly elevator. In the assembly elevator here shown the matrices may be assembled in either the upper position 80 where they rest upon the ledges 17 and 18 or in their lower position where they rest upon the flanges of the rails 14 and 16. To provide for changing the position the ledge 18 may be moved independently of the ledge 17 by manipulation of the lever 20 and while 85 one adjustment may be obtained in this manner as this ledge has several matrices upon it at a time it is necessary to do what is called "fingering" the matrices for subsequent adjustment. By the use of the improvements now to be described the ledges 17 and 18 may be made in one piece and be 90 stationary and the matrices individually assembled upon the elevator in upper or lower 95 position without "fingering".

The usual device for feeding the matrices one at a time upon the rails of the assembly elevator is a star wheel and whenever the points on this wheel become worn it is necessary to renew the wheel to obtain proper feed of the matrices. To provide a more durable construction in place of this star 100

wheel I form a slide 21 consisting of side guides 22 and a flat vertical ejector face 23, which extends transversely between the switch rails 7, said guides being slidably mounted in grooves 24 in the inner sides of the rails 7. The slide is also provided with a flat inclined plate extending backwardly and upwardly from the ejector face plate and serves to guide the matrices from the switch rails 7 to the front of the ejector face plate. This slide is continuously reciprocated during the operation of the machine by means of an eccentric 25 which is maintained in engagement with the face 23 by means of a spring 26 secured to the rail frame 27 and bearing against a pin 28 connected to the guides 22, the inner guide 22 having a slot 22' therein to permit free movement. The eccentric 25 is mounted on the usual square drive shaft 29 which is driven in the usual manner through a driving connection (not shown) with the shaft 13. With this construction the matrices pass down one at a time between the rails 7 to the guide rails 30, the parts being timed so that the ejector face 23 lies behind the matrices resting upon the rails and then the eccentric moves the ejector slide forwardly to the dotted line position shown in Fig. 3 thereby pushing the matrix onto the upper or lower rails of the assembly elevator.

The means for individually positioning the matrices in upper or lower position upon the assembly elevator consists of a slide 31 slidably mounted upon the rail 30 between said rail and the lower edge 32 of the outside rail 7, said slide carrying the pin 33 movable in a recess 34 in the front rail, said pin abutting against the ends of said recess to limit its extreme positions of movement. The front end 35 of the slide is of less thickness than the other portions so as to pass behind the front portion of the end 36 of assembly elevator. The rails 7 are so constructed as to leave a space 36' between the end 36 of the assembly elevator and the end of the rails to permit a matrix to be disposed in this space. Any suitable mechanism may be used for actuating this slide but I prefer to actuate and control its movement from the control board of the machine, this being accomplished through a bell crank lever 37 having one end 38 loosely engaging in a slot 39 in the slide 31 and the other end 39 being pivotally connected to a link 40 which is connected to a key member 41 which may be placed in the key board adjacent thereto so as to be in easy reach of the operator.

While I have shown a single slide adjacent one of the rails it will be obvious to those

skilled in the art that another slide may be used adjacent the inside rail or the slide may be located between the rails.

With this construction when it is desired to position the matrices individually in their upper position, the slide 31 is moved forwardly to bring its end 35 against the adjacent end of the upper ledge or shelf of the assembling elevator and across the outer side of the space 36' so that when the matrix moves down from the rails 7 it rests upon the top of the slide 31 and is then pushed into the upper support of the assembly elevator by the ejector mechanism previously described. So long as the slide is in this position the subsequent matrices will be delivered to their upper position and when it is desired to position any one or more of the matrices in their lower position the slide 31 is moved back permitting the matrix to drop down from the rails upon the rail 30 and be thence delivered by the ejector to the lower position rails of the assembly elevator. The depression of the key will through the link 40 and lever 37 move the slide 31 forwardly and an upward pull on the key will move the slide 31 back. Thus with this construction the individual position of each matrix upon the assembly elevator may be controlled and determined preferably from the key board without the necessity for "fingering" the matrices so that any variety of positions of the matrices with respect to each other on a line may be readily and quickly obtained.

I am aware that the details of construction herein shown and described are capable of some modification and change, and I therefore desire it to be understood that such changes in construction as come within the scope of the appended claims I deem to be within the spirit of my invention.

What I claim as my invention is—

1. In an assembler of the linotype machine, the combination with the assembly elevator and the rails leading thereto, of a matrix feed device having a flat vertical face and a flat inclined upward extension to guide the matrices from the rails to the front of the flat vertical face, and means for reciprocating said feed device.

2. In a linotype machine, the combination with the assembly elevator and the rails leading thereto, of a matrix feed device having a flat vertical face and also a flat inclined upward extension from said face, and an eccentric means for reciprocating said feed device.

In testimony whereof, I affix my signature.

ERWIN O. E. VOLKMAN.
